(74) *Attorney, Agent, or Firm* — Hoffmann & Baron, LLP

(57) **CLAIM**

The ornamental design for a vacuum cleaner, as shown and described.

DESCRIPTION

FIG. 1 is a top front perspective view of a vacuum cleaner showing our new design;
FIG. 2 is a left side view thereof;
FIG. 3 is a right side view thereof;
FIG. 4 is a front side view thereof;
FIG. 5 is a back side view thereof;
FIG. 6 is a top plan view thereof;
FIG. 7 is a bottom plan view thereof;

FIG. 8 is a top perspective view of an alternative embodiment of a vacuum cleaner showing our new design;
FIG. 9 is a left side view thereof;

FIG. 10 is a right side view thereof;

FIG. 11 is a front side view thereof;

FIG. 12 is a back side view thereof;

FIG. 13 is a top plan view thereof; and,

FIG. 14 is a bottom plan view thereof.

The broken lines shown in the figures are included for the purpose of illustrating portions of the vacuum cleaner that form no part of the claimed design.

1 Claim, 14 Drawing Sheets
